UNITED STATES PATENT OFFICE.

EDWARD E. CLEMENT, OF WASHINGTON, DISTRICT OF COLUMBIA.

ELECTRICALLY-ILLUMINATED CLOCK.

1,096,682.

Specification of Letters Patent.

Patented May 12, 1914.

Original application filed April 18, 1910, Serial No. 556,213. Divided and this application filed June 29, 1910. Serial No. 569,608.

To all whom it may concern:

Be it known that I, EDWARD E. CLEMENT, a citizen of the United States, residing at Washington, in the District of Columbia, have invented certain new and useful Improvements in Electrically-Illuminated Clocks, of which the following is a specification, reference being had therein to the accompanying drawing.

10 My invention relates to electric clocks and has for its object the production of an illuminated dial which may be employed either by itself or in connection with a mechanical clock; and which during the dark 15 hours will show successively illuminated portions corresponding to the hour and minute hands of the mechanical movement.

The present application is a division of my prior application, Serial No. 556,213, 20 filed April 18, 1910, in which a complete system of circuits, switches, driving mechanism, dials, chimes, etc., is disclosed. I shall claim herein only the dial and associated parts, and for the latter including the 25 actuating circuits, I refer not only to the aforesaid application, but also to Letters Patent No. 920,024 granted to me April 27, 1909, and to my prior application Serial No. 498,369, filed May 25, 1909.

30 My invention is illustrated in the accompanying drawing in which—

Figure 1 is a face view of a quadrant sector of a dial having non-opaque portions representing the hands in different positions and means for illuminating the same in succession. Fig. 2 is a similar view of a modification. Fig. 3 is a radial cross section of Fig. 1. Fig. 4 is a similar radial cross section of Fig. 2.

40 Referring to the drawings, A is the dial, mounted on any suitable frame, and painted or otherwise provided with opaque portions A', leaving transparent or translucent portions A² and A³ representing the hour and minute hands respectively in successive angular positions around the dial at one minute intervals. The outer transparent portion A² represents the minute hand and the inner portion A³ represents the hour hand.

45 It will be noted these are so shaped that when illuminated together they form a complete minute hand extending from the center to the circumference; but when the portion A³ is illuminated by itself, it represents 50 the hour hand only. Thus I may produce

all the positions of both hands economically by combining these different indications.

In order to illuminate the transparencies representing the hands, I provide lamps M and H, the former relating to the minute hands, and the latter relating particularly to the hour hands. These lamps are in pairs, each pair inclosed in a radial chamber or box C' whose walls cut off all side rays and which is provided with a partition C² to confine the rays of each lamp to its own portion of the transparency. These boxes C' are also located at one minute intervals all around the clock dial, each box lying directly under one of the transparencies A² and A³. The illumination of a particular lamp H will light up the corresponding hour hand only, but the illumination of both H and M will light up both the hour and minute portions so as to show the complete minute hand. The chamber containing the lamp H is provided with a reflector h as shown in Figs. 3 and 4. On this dial the fixed numerals 1, 2 and 3, etc., may be shown in any desired manner, but preferably will be transparencies similar to the hands permanently illuminated from behind the dial by small fixed lamps constantly burning.

Referring now to Fig. 2, I have therein shown a modification in which radial sets of jewels are employed in an opaque dial instead of the painted transparent figures of the hands. These jewels may be made in any shape or any size desired and are illuminated in the same manner as the transparencies A² and A³. In one portion of this figure at A⁴ I have shown the dial perfectly plain, and in this case it is supposed to be of ground glass, with the boxes C' behind it, the same as in Fig. 1. The successive lighting of the lamps H and M will produce the impression of hands, without any outlines on the dial, and this is a modification which can most easily be applied to existing mechanical tower clocks, which have generally had their dials illuminated throughout, so as to show the moving hands in their various positions. It is quite obvious that to provide auxiliary lamps H and M in boxes C' behind the usual ground glass or other translucent dial or in front of a solid dial, will not only result in greater efficiency, but in great economy of current. In such cases a central

lamp or lamps would be employed, such as the ring lamps *a*, and also fixed lamps around the periphery to illuminate the hour numerals and if desired the minute points.

5. I am aware that a number of modifications can be made in the invention thus described, such for example in covering each box *C'* with glass and painting the outline of hands on the glass. I desire it understood however that all non-essential changes and modifications are contemplated by me as within the scope and purview of the invention and of the appended claims.

It will be understood that the lamps *H* and *M* are to be lighted in succession by the circuits in any of my prior cases hereinbefore referred to which are not at present described.

Having thus described my invention what I claim and desire to secure by Letters Patent is—

1. In a system of the class described, an electric clock without moving parts, comprising the following instrumentalities: a series of boxes or channels arranged radially in a circular figure, corresponding to successive positions of clock hands advancing minute by minute around the dial, each channel having a partition dividing it into two portions and each portion free of partitions throughout its length, that portion extending from the partition to the center corresponding to the hour hand of the clock, and that portion extending from the partition outwardly corresponding to the extension or head of the minute hand; and separate illuminating means included in each portion of each box, so arranged that the illumination of the inner portion of one box will suggest the hour hand in a corresponding position, the illumination of both portions of any box will suggest the minute hand in that position, and at points where the hands would pass each other, as at twelve o'clock noon, the illumination of both portions of one box or channel but no other will suggest the coincidence of the hands.

2. In a system of the class described, an electric clock without moving parts, comprising the following instrumentalities: a series of illuminable boxes or channels arranged radially in a circular figure to represent the hour and minute hands of a clock in corresponding angular positions, a series of non-illuminable spaces alternating therewith, means within said illuminable boxes to cut off radial rays which would cause interference between the hour and minute indications.

3. In a system of the class described, an electric clock without moving parts, comprising the following instrumentalities: a dial of light transmitting material, walls forming a series of illuminable spaces arranged radially in a circular figure around

one side of said dial, their angular positions corresponding to those successively occupied by the hour and minute hands of an ordinary clock in progressing around the dial, said dial being partially opaque to define, in front of each space when illuminated, a radial bar of light shaped so that its outer end will represent the head of a minute hand, and an intermediate point the head of an hour hand.

4. In a system of the class described, an electric clock without moving parts comprising the following instrumentalities: walls forming a series of spaces arranged radially in a circular figure every other one of which is provided with means of illumination and with a translucent cover or front wall, the alternate spaces being without illumination and having opaque front walls which adjoin the said translucent covers or front walls.

5. In a system of the class described, an electric clock without moving parts comprising the following instrumentalities: walls forming a series of radial illuminable spaces arranged in a circular figure each space having opaque sides and a translucent cover or front wall adapted when the chamber is illuminated to define a radial bar of light simulating in contour the superposed hands of a clock and in such proportions of length that the outer end of the hour hand terminates inside the head of the minute hand, and a partition within each space situated at said point of termination.

6. In a system of the class described, an electric clock without moving parts comprising the following instrumentalities: walls forming a series of radial illuminable spaces arranged in a circular figure each space having opaque sides and a translucent cover adapted, when the space is illuminated, to define a radial bar of light simulating in contour the superposed hands of a clock in such proportions of length that the outer end or point of the hour hand terminates inside the head of the minute hand, a partition within the chamber situated at said point of termination, and a second partition at the point of the minute hand together with means for continuously illuminating the space outside of the said second partition for indicating the minute graduations around the dial of the clock.

7. In a system of the class described, an electric clock without moving parts comprising the following instrumentalities: walls forming a series of radial spaces arranged in a circular figure corresponding to successive positions of clock hands advancing minute by minute around the dial, each space having a partition dividing it into two parts, each of said parts being free of partitions throughout its length, whereby the whole of each part may be illuminated by a single source of light, the inner one of said parts

to represent the hour hand, the inner and outer parts together to represent the minute hand.

8. In a system of the class described, an electric clock without moving parts, comprising the following instrumentalities: a plurality of channel members radiating from a common center, and an electric lamp secured within the outer portion of each channel member and arranged to throw its light out of the open top of the channel throughout its entire length, whereby the intensity of illumination will be greater near the extremity of the channels.

15 9. In a system of the class described, an electric clock without moving parts, comprising the following instrumentalities: a plurality of channel members radiating from a common center, an electric lamp secured within the outer portion of each channel member, and a reflecting member within each channel shaped so as to receive light radiating from the lamp toward the center and reflect it upwardly throughout the length of the channel, producing a radial bar of light with increased brightness at its outer extremity.

10 10. In a system of the class described, an electric clock without moving parts, comprising the following instrumentalities: a plurality of channel members or boxes C radiating from a common center, said boxes having closed ends, bottoms and sides, but open tops, electric lamps secured in the outer portions of the channels, and a reflector h in each channel extending from the lamp toward the inner end of the channel and bending upwardly so as to reflect all light received from the lamp out of the open top of the channel.

40 11. In a system of the class described, an electric clock without moving parts, comprising the following instrumentalities: a circular succession of radial boxes or chan-

nels C' open in front for the emission of light, a partition c² in each box dividing it into two sections corresponding in length to the hour and minute hands of a clock respectively, an electric lamp H secured within and at the outer extremity of the hour portion of the box, and a lamp M similarly secured within the minute portion, whereby the successive lighting of the lamps H will produce apparent movement of an hour hand around the dial, while the successive lighting of pairs of lamps H and M will produce apparent movement of a minute hand around the dial.

12. An electric clock comprising a plurality of radially arranged light boxes of substantially uniform length which radiate from the periphery of a central circle, means for illuminating each of said radial light boxes, and means permanently illuminating said central circle, whereby each radial beam of light emanates from said central circle of light.

13. In a system of the class described, an electric clock without moving parts comprising the following instrumentalities: a circular series of adjacent boxes extending radially from a common point, each box having opaque side walls and each box occupying the position of an hour or minute clock hand at one point in its rotation around the dial, an independently illuminable source of light in each box, and means for projecting the light from each box when its source of light is illuminated, so as to convey to the eye of the observer substantially the outline of an hour or minute clock hand.

In testimony whereof I affix my signature in presence of two witnesses.

EDWARD E. CLEMENT.
